AIR FILTER

Edwin G. Pierce, Cleveland, Ohio

Application January 8, 1944, Serial No. 517,491

1 Claim. (Cl. 128—147)

1 This invention relates to air filters and more particularly to a compact emergency filter for use in maintaining life while leaving an environment where a toxic gas has been liberated and seeking a place of safety.

The objects of the present invention include the provision of a compact air filter of simple and inexpensive design that can be carried in the clothes of a worker or at his bench so that it is conveniently within his reach at all times; that is sealed when not in use to prevent the deterioration of its filter charge; that may be adapted for absorbing or neutralizing the poisonous content of a particular gas that might be liberated unexpectedly on the failure of a container, of equipment, or the like; that is available for use when needed with a minimum of effort and delay; and that will save the lives of many workers and people which lives would be lost if some provision is not made for their safety in escaping from a confined space in which a poisonous gas may be abruptly and unexpectedly liberated, into the open air or other place of safety.

With the above and other objects in view which will be apparent from the following discussion to those who are informed concerning the practices of preserving human life in the presence of poisonous gases, mists, sprays and the like, that may result from an explosion of equipment, the failure of a storage tank, or the like, illustrative embodiments of the present invention are disclosed in the accompanying drawings wherein:

Fig. 1 is a side elevation partly cut away and in section of a device that embodies the present invention;

Fig. 2 is a fragmentary elevation of a part of the device that is shown in Fig. 1 with a mouthpiece in its extended condition ready for use;

Fig. 3 is a fragmentary elevation of the mouthpiece carrying end wall of the device that is shown in Fig. 1;

Fig. 4 is an enlarged fragmentary elevation partly in section and partly broken away of the mouthpiece and its seat separated from each other as shown in Fig. 2;

Fig. 5 is a fragmentary plan view from above of the closure that seals the intake orifice in the device that is shown in Fig. 1;

Fig. 6 is a fragmentary view from below of the intake orifice seal shown in Fig. 5 taken from the line 6—6 in Fig. 1;

Fig. 7 is an edge elevation with parts in section of a preferred nose closure for use with the device shown removably mounted upon a fragmentary

2 edge elevation of the device that is shown in Fig. 1;

Fig. 8 is a side elevation of the nose closure shown in Fig. 7 adjustably mounted upon a fragmentary side elevation of the device that is shown in Fig. 1;

Fig. 9 is a sectional view of the nose closure that is shown in Fig. 7, taken along the line 9—9 of Fig. 8;

Fig. 10 is a fragmentary view partly in section of an adaptation of the device that is shown in Fig. 1 to include a tank of compressed oxygen;

Fig. 11 is an elevational view, partly broken away and in section, of a circular form of device that embodies the present invention having a spiral gas channel disposed inwardly thereof;

Fig. 12 is a fragmentary plan view of the intake orifice seal and part of the nose closing cushion of the device that is shown in Fig. 11, taken from the line 12—12 thereof; and

Fig. 13 is a section of the device that is shown in Fig. 11, taken along the line 13—13 of Fig. 11, showing its extensible mouthpiece in its retracted and sealed position.

The rectangular form of air filter that forms a part of the present invention comprises a canister 1, the interior of which is subdivided in any desired manner, as by the partitions 2 or the like, into a continuous gas conducting channel from an intake port 3 to a tubular mouthpiece 4 to which suction may be applied to cause a gas to pass thru the canister.

Screens 5 and 6, that are stretched over and cemented along their rims to the apertured partitions 7 and 8, minimize the loss of fines from the particular charge of poisonous gas absorbing or neutralizing material with which the canister 1 may be charged. Partition 7 is arranged between one of the partitions 2 and one of the end walls of the canister in proximity to but spaced from the intake port 3 and partition 8 is arranged between another partition 2 and the other end wall of the canister and is arranged in proximity to but spaced from the tubular mouthpiece 4.

After the canister is charged, a gas impervious glue is applied to the edges of the canister, its partitions 2 and its partitions 7 and 8. A canister side is then applied and bonded thereto for sealing up the device after which it is ready for use.

The tubular mouthpiece 4 is retractable and makes close sliding engagement within a sleeve 10 that has one of its ends secured to an end wall of the canister 1, as by gas impervious glue 11, or the like. As illustrated, the outer end of sleeve

10 is flush with an opening in the canister which opening is spaced from the intake port 3 and the tubular mouthpiece 4 is slidably mounted in the opening and sleeve 10 and has secured thereto a ring 12 that abuts against the inner edge of the sleeve 10 when the mouthpiece 4 is drawn out from the canister preparatory to using the device at which time the inner orifice of the mouthpiece is open and the tubular mouthpiece provides an outlet from the canister. The mouthpiece 4 preferably terminates inwardly of the canister 1 in a frusto-conical edge 13 that seats within a mating depression 14 in one of the partitions 2 which acts as a wall to thereby provide a gas-tight seal between the inner end of the mouthpiece 4 and the partition 2 that it abuts when the mouthpiece is in its innermost position. The depression 14 may contain a thin coating of wax or the like, not shown, to further perfect the gas-tight seal for the inner end of the mouthpiece 4, if preferred. A gas sealing packing 15 is disposed around the exposed end of the mouthpiece 4 and is secured to the outer surface of the end wall of the canister 1 in any suitable manner, as by a ring 16 or the like, for minimizing the entrance of gas from outside of the device between the mouthpiece 4 and the sleeve 10 in which it slides. The exposed end of the mouthpiece 4 preferably is provided with a flange 17 that provides it with a finger grip when it is desired that the mouthpiece is to be drawn outwardly of the canister 1 and for a tooth grip when the mouthpiece 4 is inserted into the user's mouth.

The intake orifice 3 is preferably sealed in such a manner that, upon the removal of the seal, an intake orifice of approximately a predetermined size results. With this object in view a sealing tab 20 is attached continuously along its periphery around the intake orifice 3 to the top of the canister 1 to make a gas-tight seal over the intake orifice 3. On the under side of the tab 20, a stiff member 21 is arranged which is attached to a wire ring 22 extending above the tab by any suitable means, such as a loop of adhesive tape 23 or the like, that has its ends bonded to the bottom of the tab 20. The assembly is sealed against gas leakage by a non-drying adhesive gas impervious coating 24 or the like, that is positioned thereover. Any other suitable arrangement may be adopted for removing the major part of the tab 20 when the device is to be used.

In operation the device is first removed from a suitable protective cover, such as a sealing cover of Cellophane or the like, somewhat as a package of cigarettes or the like is opened. The intake orifice is then opened by tearing off the tab 20. The mouthpiece flange 17 is then grasped between the fingers and the mouthpiece 4 is drawn out into its operative position, as shown in Fig. 2 of the drawings at which time the inner orifice of tube 4 is exposed to provide an outlet from the canister. The exposed end of the mouthpiece 4 is then inserted into the mouth of the user and the device is ready to function. As the user inhales air thru the mouthpiece 4, the air that he inhales will previously have passed through the intake orifice 3 and the poisonous gas filtering or neutralizing charge disposed within the gas conducting channel within the canister so that air inhaled by the user will have been purified of any deleterious gases, mists, dusts or other material that may have been mixed therewith when it enters the intake orifice 3 of the canister part of the device.

Provision is made for those individuals who pre-

fer closed nostrils when wearing an air purifying device. For this purpose a clamp 25 yieldingly grips the sides of the canister 1 when slid down thereover. The clamp 25 continues upwardly in a frame 26 that is soldered, welded or otherwise secured thereto. The frame 26 carries inwardly thereof a pair of opposed laterally disposed gas impervious resiliently yielding pads 27 for closing nares that open toward the sides of the user's nose or for compressing the side walls of a normal nose toward its septum and a gas impervious resiliently yielding pad 28 therebetween and below the pads 27 for closing nares that open downwardly and for compensating for differences in the distances between the lips and noses of different users of the device.

An adaptation of the device that is shown in Fig. 1 for the inclusion of a cylinder of compressed oxygen is shown in Fig. 10 of the drawings. In this construction the canister 30 is preferably compartmented by a desired number of partitions 31 to provide a continuous gas conducting channel from an intake orifice thru a screen 32 and a ring of apertures 33 opening into a compartment in which a mouthpiece 4 is mounted. A partition 34 has an aperture 35 registering with an outlet from a tank 36 that contains compressed oxygen and that is installed in a part of the gas conducting channel of the canister as shown. The flow of oxygen into the compartment in which the mouthpiece 4 is disposed is controlled by suitable means such as a valve key 37 that extends to outside of the canister 30. A gasket or packing 38 seals the orifice in the end wall of the canister 30 in which the valve key 37 is disposed against the entrance of poisonous gas into the canister.

In operation, this form of canister provides the user with a limited supply of pure oxygen when the seal over the intake orifice is not broken, or an oxygen enriched supply of purified air when the seal over the intake orifice is opened.

A circular form of the canister 40 is shown in Figs. 11-13, inclusive, of the drawings. The canister 40 is provided with a continuous gas conducting channel by a continuous spiral partition 41 that extends from an intake orifice 42 to a partition provided with an opening 43 for the disposition of a desired poison gas absorbing or neutralizing charge within the gas conducting channel so provided. The canister 40 is shown with one side partly broken away so that its details of construction will be illustratively apparent. When fully charged a gas impervious glue is applied to the edges of the outside wall of the canister 40 and its partition 41 and the cover is mounted and secured thereon. The loss of fine particles from the charge is minimized by the disposition of the screens 44 and 45 over the intake orifice 42 and the opening 43, respectively, of the canister 40. The intake orifice 42 is releasably sealed with a suitable tab 46 that has gas impervious glue around the periphery of the intake orifice 42 so that the tab 46 may be conveniently torn away to provide an intake orifice of a predetermined size when gripped by a free end 47 thereof and the tab 46 is torn away from the outer surface of the canister 40.

A tubular mouthpiece 50 is disposed in a compartment within the canister 40 which communicates through the opening 43 with the gas absorbing or neutralizing charge in the gas conducting channel. The mouthpiece 50 is preferably of the retractable type, sliding in a sleeve 70 51 that is secured to the inner face of one of

the sides of the canister 40 by glue 52 or the like, and gas-sealed in its engagement therewith in a desired manner, as by a sufficiently gas-impermeable gasket or packing 53 that is disposed upon the outer surface of a side of the canister around the mouthpiece 50. The outer end of sleeve 51 is flush with an opening in one wall of the container and the tubular mouthpiece 50 is slidably mounted in the opening and sleeve 51. Suitable means, such as a ring 54, is secured on the inner end of the mouthpiece 50 to arrest its movement outwardly of the canister 40 by abutting against the inner edge of the sleeve 51 when the mouthpiece 50 is in its outermost position at which time the inner orifice of mouthpiece 50 provides an outlet from the canister. The inner end of the mouthpiece 50 preferably terminates in a frusto-conical edge 55 that is adapted for making gas-sealing engagement with the inner surface of the opposite side of the canister 40 in any desired manner when the mouthpiece is in its innermost position, as by seating into a corresponding depression 56 therein that may, or may not as preferred, contain a suitable gas-impermeable sealing material, such as wax or the like, as previously described. The exposed end of the mouthpiece 50 is preferably provided with a flange 57 that provides a finger and tooth grip on the mouthpiece 50 when the device is to be used.

The periphery of the canister 40 is depressed, as at 60, sufficiently to properly position, with respect to the mouthpiece 50, a gas-impermeable resiliently cushioning material 61 therein for closing the nose of a wearer. The cushioning material 61 is secured within the depression 60 in any suitable manner, as by being cemented or the like therein.

In operation the free end 41 of the tab 46 is grasped between the fingers and the tab 46 is torn away from the canister 40, leaving the intake orifice 42 in its open condition. The flange 57 on the exposed end of the mouthpiece 50 is then grasped between the fingers and the mouthpiece 50 withdrawn from the canister 40 until its ring 54 abuts the inner end of the sleeve 51. The user's nose is then pressed down into the gas-impermeable cushion material 61 to close the nose so that no poisonous gas that may be in the contaminated air surrounding the user is inhaled thru the nose and the user inhales purified air that has passed thru the canister charge thru the mouthpiece 50 into the user's mouth. The user preferably exhales thru the outer corners of his mouth. If the user prefers he may remove his nose from the cushion material 61 for the purpose of exhaling.

The nose sealing device that is shown in Figs. 7-9, inclusive, of the drawings preferably has

the pads 27 secured by a cement or the like, to the opposed inner faces of the frame 26 adjacent the upper edges thereof so that they close nares that open laterally away from the nose or compress the side walls of a normal nose toward the septum thereof. The pad 28 is similarly secured by cement or the like, to the opposed inner faces and the bottom of the frame 26 and preferably not to the pads 27. With this construction the pad 28 is free to move downwardly independently of the pair of pads 27 where this function improves the nose sealing properties of the device for a particular user.

It is to be understood that the various forms of the parts of the filtering devices that are disclosed herein are submitted for the purposes of illustrating and describing the present invention and that various modifications may be made therein without departing from the present invention as defined by the appended claim.

20 What I claim is:

Apparatus of the class described comprising a rectangularly-shaped canister having an inlet port adjacent one end thereof and an opening adjacent the other end, a plurality of baffles arranged in staggered relation to provide a circuitous channel for receiving an air-purifying material and with one of said baffles being arranged to form a wall opposite said opening, a tubular mouthpiece mounted in said opening to form a close sliding fit, the inner end of which mouthpiece engages said wall to seal its inner orifice when the mouthpiece is forced inwardly into engagement with said wall, means for maintaining said air-purifying material in spaced relation to said mouthpiece and said mouthpiece being of sufficient length to extend through said opening with its outer end arranged in proximity to the outer surface of said canister and being movable outwardly from said wall to provide an outlet passage therethrough for the purified air from said canister.

EDWIN G. PIERCE.
